(57) **CLAIM**

The ornamental design for a solar collector array and support body supporting the solar collector array, as shown and described.

DESCRIPTION

FIG. 1 is a front perspective view of a solar collector array and support body supporting the solar collector array showing my new design;

FIG. 2 is a left-side elevation view thereof, the right side being a mirror image;

FIG. 3 is a rear perspective view thereof; and,

FIG. 4 is another rear perspective view thereof, shown in a stowed position.

1 Claim, 4 Drawing Sheets

FIG. 1

FIG. 2

FIG. 3

FIG. 4
